US00D785474S

(12) **United States Design Patent** (10) **Patent No.:** **US D785,474 S**
(45) **Date of Patent:** **** May 2, 2017**

(54) **SURFACE TOOL**

(71) Applicant: **Zircon Corporation**, Campbell, CA (US)

(72) Inventor: **Barry Wingate**, San Jose, CA (US)

(73) Assignee: **Zircon Corporation**, Campbell, CA (US)

(**) Term: **15 Years**

(21) Appl. No.: **29/549,159**

(22) Filed: **Dec. 18, 2015**

(51) LOC (10) Cl. **10-04**

(52) U.S. Cl.

USPC **D10/70**; D10/62; D10/65

(58) **Field of Classification Search**

USPC D10/53, 62, 65, 69, 70, 78, 81; D13/168;

D16/135; D24/113, 186, 187, 233

CPC G01C 9/06; G01V 3/15; G01V 3/088

(57) **CLAIM**

The ornamental design for a surface tool, a described and shown.

DESCRIPTION

FIG. 1 is a perspective view of a surface tool according to a preferred embodiment of the present invention;

FIG. 2 is a top plan view thereof;

FIG. 3 is a bottom plan view thereof;

FIG. 4 is a right side plan view thereof;

FIG. 5 is a left side plan view thereof;

FIG. 6 is a front elevational view thereof; and,

FIG. 7 is a rear elevational view thereof.

The broken lines showing parts of a surface tool are for the purpose of illustrating portions of a surface tool that form no part of the claimed design.

1 Claim, 5 Drawing Sheets
